UNITED STATES PATENT OFFICE

2,428,287

SHORTING PISTON FOR WAVE GUIDES

Ernest G. Linder, Princeton, N. J., assignor to
Radio Corporation of America, a corporation
of Delaware

Application May 18, 1943, Serial No. 487,515

8 Claims. (Cl. 178—44)

1

This invention relates generally to super-high frequency transmission apparatus, and more particularly to a shorting piston for a conventional wave guide of rectangular cross-section.

Heretofore, various types of terminating pistons for wave guides have been employed to vary the effective length of resonant wave guide sections. However, all such slideable pistons have introduced serious power losses and extraneous wave reflections due to faulty electrical contact between the piston and the interior faces of the wave guide. The terminating piston carries considerable current in a wave guide transmission system in which any appreciable power is transmitted. It also is highly desirable that the shorting piston maintain substantially uniform orientation as it is adjusted longitudinally along the wave guide.

The instant invention effectively overcomes the various disadvantages of older devices mentioned heretofore, since the adjustable piston includes a novel spring contact arrangement which insures satisfactory contact between the piston and the adjacent interior walls of the wave guide, and also provides satisfactory support for maintaining the piston face substantially normal to the axis of wave propagation.

The friction between the piston spring contact and the interior wave guide faces is also maintained at a practical value which permits smooth adjustment of the longitudinal position of the piston by means of a simple, externally located screw feed.

Among the objects of the invention is to provide an improved shorting piston for a super-high frequency wave guide. Another object is to provide an improved shorting piston for a super-high frequency wave guide of rectangular cross-section, wherein the longitudinal position of the piston within the guide may be adjusted by means of an externally located screw feed adjusting device. A further object of the invention is to provide an improved shorting piston for a rectangular wave guide super-high frequency transmission line, wherein the piston includes a novel spring contact device which insures good contact, smooth operation, and constant piston orientation within the guide. A further object of the invention is to provide an improved shorting piston for a super-high frequency wave guide, wherein the operative face of the piston is a concave surface substantially normal to the axis of wave propagation. An additional object is to provide an improved shorting piston and improved means for coupling a concentric trans-

2

mission line to a super-high frequency wave guide, wherein the transmission line is coupled to the guide continuously adjacent a point of maximum current distribution, notwithstanding longitudinal adjustment of the piston along the guide axis.

The invention will be described in further detail by reference to the accompanying drawing, of which Figure 1 is a cross-sectional view of a first embodiment of the invention, taken along the line I—I of Fig. 2; Figure 2 is a cross-sectional view of the same embodiment of the invention, taken along the line II—II of Fig. 1; and Figure 3 is a cross-sectional view of a second embodiment thereof. Similar reference numerals are applied to similar elements throughout the drawing.

Referring to the drawing, a wave guide 1 of rectangular cross-section is terminated by an apertured plug 2, which is secured in the end of the guide by means of screws 3. An adjustable shorting piston, disposed within the guide, includes a frame 4 substantially coextensive with the cross-sectional dimensions of the interior of the wave guide. The frame 4 includes a slotted portion 5 along two opposite faces thereof.

A U-shaped spring contact member 6 includes ends 7 formed to fit within the slots 5, parallel faces adapted to provide sliding contact with two inside faces of the guide 1, and a slightly concaved working face 9 substantially normal to the axis of wave propagation within the guide. Small screws 10 fasten the ends 7 of the U-shaped spring contact member to the piston frame 4 within the slots 5. Auxiliary pressure springs 11 are inserted under the parallel faces 8 of the contact spring 6, and anchored in suitable slots in the sides of the frame 4. These auxiliary pressure springs tend to expand the U-shaped contact spring to the shape of the inside surface of the guide, and insure satisfactory contact and smooth operation as the piston is moved longitudinally along the guide. Either, or both, the contact spring member 6 and the auxiliary pressure springs 11 may include longitudinal slots 16 or other means to facilitate conformation thereof to the inner wall of the guide.

An adjusting screw 12 is anchored to the piston frame 4 and extends through the aperture in the terminating plug 2 a predetermined distance outside of the end of the wave guide. A knurled adjusting nut 13, threaded to receive the adjusting screw 12, includes a shoulder 14 which extends inside of the guide terminating plug 2. A pawl 15, attached to the inside surface of the terminating plug 12, engages the shoulder 14 to prevent

longitudinal movement of the adjusting nut 13. It will be seen that, as the adjusting nut 13 is rotated, the adjusting screw 12, and hence the shorting piston, will be moved longitudinally along the interior of the wave guide.

Figure 3 is similar to Figures 1 and 2, with the exception that the adjusting screw 12 is hollow, and includes an insulated central coaxial conductor 17, which extends through an aperture 18 in the spring contact working face 9, and terminates in a coupling loop 19 which is connected to the end of the screw 12. The proportions of the coaxial conductors 12, 17 may be selected to provide desired surge impedance, and the outer extremities thereof may be coupled in any conventional manner to an external line. It will be seen that the coupling loop 19 is coupled continuously to the wave guide 1 at a point of substantially maximum current distribution notwithstanding longitudinal adjustment of the shorting plug along the guide.

If desired, the longitudinal position of the shorting piston may be calibrated by including suitable indicia on the portion of the shorting screw 12 which projects through the adjusting nut 13.

Thus, the invention described comprises an improved shorting piston for a super-high frequency wave guide of rectangular cross-section, wherein substantially improved contact and piston adjustment are provided by means of a novel spring contact, and wherein an external line may be coupled efficiently to the guide at a point of maximum current distribution.

I claim as my invention:

1. A shorting-piston for a super-high frequency wave guide comprising a conductive frame substantially coextensive in cross-section with said guide, a spring contact member fastened to the sides of said frame adjacent the sides of said guide and shaped to present a concave surface substantially normal to the axis of wave propagation in said guide, and spring members fastened to said frame and disposed intermediate said frame and said contact member for increasing the pressure exerted by said contact member on said guide faces.

2. Apparatus of the type described in claim 1 including a lead screw fastened to said frame and extending longitudinally outside of said guide, and an adjusting member threaded to said screw for adjusting externally of said guide the longitudinal position of said piston therein.

3. A shorting-piston for a super-high frequency wave guide comprising a conductive frame substantially coextensive in cross-section with said guide, a spring contact member fastened to the sides of said frame adjacent the sides of said guide and shaped to present a concave surface substantially normal to the axis of wave propaga-

tion in said guide, and substantially flat spring members fastened to said frame and disposed intermediate said frame and said contact member for increasing the pressure exerted by said contact member on said guide faces.

4. Apparatus of the type described in claim 1 including a threaded apertured conductive wall terminating the end of said guide adjacent said shorting plug, and means operable through said apertured wall for adjusting the longitudinal position of said piston in said guide.

5. A shorting-piston for a super-high frequency wave guide comprising a conductive frame substantially coextensive in cross-section with said guide, a spring contact member fastened to the sides of said frame adjacent the sides of said guide and shaped to present a surface having at least portions thereof substantially normal to the axis of wave propagation in said guide, and substantially flat spring members fastened to said frame and disposed intermediate said frame and said contact member for increasing the pressure exerted by said contact member on said guide faces.

6. Apparatus of the type described in claim 1 characterized in that at least one of said spring and said spring contact members include longitudinal slots to facilitate conformation thereof to the inner surface of said guide.

7. Apparatus of the type described in claim 5 characterized in that at least one of said spring and said spring contact members include longitudinal slots to facilitate conformation thereof to the inner surface of said guide.

8. Apparatus of the type described in claim 1 including a hollow externally threaded cylindrical conductor fastened to said frame and extending longitudinally outside of said guide, a coaxial center conductor extending through said hollow conductor spaced therefrom, a coupling loop terminating the inner ends of said coaxial conductors extending into said guide through an aperture in said concave surface of said spring contact member, and an adjusting member threaded to said externally threaded conductor for adjusting externally of said guide the longitudinal position of said piston and said loop therein.
